UNITED STATES PATENT OFFICE

HERBERT F. OBERGFELL, OF RIVER FOREST, ILLINOIS, ASSIGNOR, BY MESNE ASSIGNMENTS, TO ASSOCIATED ELECTRIC LABORATORIES, INC., OF CHICAGO, ILLINOIS, A CORPORATION OF DELAWARE

DESIGN FOR A TELEPHONE DESK STAND

Application filed May 18, 1931. Serial No. 39,888. Term of patent 14 years.

To all whom it may concern:

Be it known that I, HERBERT F. OBERGFELL, a citizen of the United States of America, residing at River Forest, in the county of Cook and State of Illinois, have invented a new, original, and ornamental Design for Telephone Desk Stand, of which the following is a specification, reference being had to the accompanying drawings, forming a part thereof.

Fig. 1 is a plan view showing my new design of a telephone desk stand; Fig. 2 is a front view; and Fig. 3 is a side view.

What is claimed is:

The ornamental design for a telephone desk stand, as shown.

In testimony whereof, I have hereunto set my hand this 13th day of May, 1931.

HERBERT F. OBERGFELL.
